UNITED STATES PATENT OFFICE.

STEWART L. SHARPLESS, OF MILWAUKEE, WISCONSIN.

TRIPPING MECHANISM FOR PRINTING MACHINERY.

Application filed October 28, 1925. Serial No. 65,353.

My invention relates to tripping mechanism for printing machinery, and is exemplified in connection with a printing press having a rotary printing member on which 5 tripping mechanism operates for placing the printing couple in on-impression relation or in off-impression relation.

It is the object of my invention to provide novel means whereby a member of a printing couple is placed in off-impression position prior to the normal coercive printing relation between the members of said printing couple, and whereby said member is maintained in said off-impression position 10 throughout the normal printing movement between said members; further, to provide novel means whereby a member of a printing couple is placed in on-impression position prior to the normal coercive printing 15 relation between the members of said printing couple, and whereby said member is maintained in said on-impression position throughout the normal printing movement between said members; and, further, to provide 20 novel means for moving a member of a printing couple into on-impression relation after a previous normal printing movement between the members of said printing couple and prior to the next succeeding normal 25 printing movement between said members, with an interim between said on-impression movement and the normal printing movement between said members, during which 30 said member may be moved into off-impression 35 position.

The term "printing movement" is used to designate that movement between the members during which the form and sheet are in opposed relation, whether or not the members 40 are in printing proximity.

It is the object of my invention further to provide novel tripping means for a plurality of printing couples so arranged as to place members of the respective printing couples in 45 off-impression position in sequence; further, to provide novel means whereby members of the respective printing couples are placed in on-impression relation in sequence; and, further, to provide novel means whereby to 50 move a rotating member of a printing couple sequentially into active relation and into inactive relation throughout different angles of the rotative movement thereof.

It is the object of my invention further to

provide novel means for timing the coercive 55 relations in the tripping means for succeeding printing couples; and, further, to provide novel means whereby the tripping movement for one printing couple is automatically transmitted to tripping mechanism for another printing couple in sequence.

It is the object of my invention further to provide novel means for rendering the tripping mechanism effective for on-impression 65 relation in the printing couple during an angular movement of the grippers of the rotating impression cylinder between the time of paper-taking action of said grippers and the time of initiation of printing impression, and for off-impression relation between said members during a succeeding angular movement of said grippers between said aforementioned times; and, further, to provide means whereby the members of the 70 printing couple remain in the relation which they occupy at the completion of said respective angular movements throughout the balance of the circle of movement of said rotative member.

It is the object of my invention further to provide novel means for controlling a tripping movement; further, to provide novel means for effecting a tripping movement; and, further, to provide novel means 75 for controlling and effecting tripping movements in successively acting printing couples automatically with relation to each other.

My invention will be further readily understood from the following description and 80 claims, and from the drawings, in which latter:

Fig. 1 is a side elevation of my improved device, shown in connection with the feed side of a rotary printing press, partly broken 85 away, having a plurality of printing couples, with the members of the latter in on-impression relation.

Fig. 2 is a side elevation of the same, viewed from the gear side of the printing 100 press.

Fig. 3 is a side elevation of the same, viewed from the feed side, partly broken away, for exposing the interior of the housing and the relations of the members of 105 the printing couples, the lower one of the latter being shown in off-impression relation and the upper one in on-impression re-

lation, with the parts of the tripping mechanism in corresponding relations.

Fig. 4 is a similar view, showing both the printing couples in off-impression relation.

Fig. 5 is a vertical cross-section of the housing, taken in the plane of the line 5—5 of Fig. 6.

Fig. 6 is a longitudinal section of the same, taken in the plane of the line 6—6 of Fig. 5.

Fig. 7 is a plan section of my improved device, taken in the plane of the irregular line 7—7 of Fig. 1.

Fig. 8 is a plan section of the same, taken in the plane of the line 8—8 of Fig. 6, partly broken away.

Fig. 9 is a plan section of the same, taken in the plane of the line 9—9 of Fig. 6.

Fig. 10 is a detail in section, taken on the line 10—10 of Fig. 1.

Fig. 11 is a vertical section of the same, taken in the plane of the line 11—11 of Fig. 10.

Fig. 12 is a vertical sectional detail, taken on the section line 12—12 of Fig. 8.

Fig. 13 is a vertical section, showing a detail of the trip control means, taken in the plane of the irregular line 13—13 of Fig. 14.

Fig. 14 is a vertical cross-section of the same, taken in the plane of the irregular line 14—14 of Fig. 13.

Fig. 15 is a side elevation showing a diagrammatic representation of the tripping mechanism for the upper impression cylinder.

Fig. 16 is a similar view of the tripping mechanism for the lower impression cylinder.

I have in the present exemplification illustrated a rotary printing press comprising a printing stand 21, in which a lower impression cylinder 22, an upper impression cylinder 23, a transfer cylinder 24, form cylinders 25, 26, 27 and 28, as well as a feed cylinder 29, are journaled. The form cylinders may be of any suitable character, and are represented as plate cylinders, on which printing plates 31, 32, 33, 34, are suitably secured, the printing surfaces of the printing plates having ink applied thereto by any suitable inking rollers, indicated for instance at 35, 36, 37 and 38. It is of course obvious that my invention is applicable to other types of printing presses, within the spirit of my invention and the scope of the appended claims.

Each of the impression cylinders is exemplified as a so-called single revolution cylinder, having a tympan surface 39 throughout substantially half its circumference, during coaction of which with the form cylinders the printing takes place, and a relief portion 40 throughout substantially the balance of its circumference, which is free of

printing effect. The form cylinders may have printing plates secured about their entire circumference. They may also have transfer impressions applied thereto, as in offset presses.

The impression cylinders and the feed cylinder are instanced as movably mounted in the frame by means which are duplicated at the respective ends of said cylinders.

The means at the feed side of the printing press will be described, and the similar means at the gear side of the printing press indicated by similar but primed reference numerals.

The impression cylinder 22 has a shaft 41 journaled in a bearing block 42 slidable in a guideway 43 of the side member of the frame 21. (See Figs. 1, 2, 3, 4, 10 and 11.) A rock shaft 44 is journaled in bearings 45 of a spacing block 46 secured to the frame, 85 and has an eccentric 47 thereon, which is operable in a slot 48 in a lug 49 of the bearing block 42, the lug being slidably received between the bearings 45.

The impression cylinder 23 has a similar shaft 51 journaled in a bearing block 52 slidable in a guideway 53 in the side member of the frame. A rock shaft 54 is journaled in bearings 55 at the respective sides of a spacing block 56 secured to the frame, 95 and has an eccentric 57 thereon, which is operable in a slot, similar to the slot 48, in a lug 59 of the bearing block 52, the lug being slidably received between the bearings 55.

The feed cylinder has a shaft 61 which is journaled in an eccentric sleeve 62, rockable in a bearing 63 in the side frame.

The paper to be printed, in the present exemplification is fed to the printing press 105 from a feedboard 65 to suitable grippers on the feed cylinder, whence it is transferred automatically to grippers 67 on a gripper shaft 68, rockable in the impression cylinder 22, and operated in suitable manner, so as to take the sheet from the feed cylinder and carry it in the rotation of the impression cylinder 22 past the form cylinders 25, 26, each of which prints a different color on the sheet. The grippers 67 automatically deliver the infeeding edge of the sheet to suitable grippers 71 on a rockable gripper shaft 72, on the transfer cylinder 24, the said grippers being operated in suitable and usual manner. The infeeding edge 115 of the sheet is automatically transferred from the latter to suitable grippers 73, on a rockable gripper shaft 74, operated in usual and suitable manner, the gripper shaft 74 being mounted on the impression cylinder 23. The impression cylinder 23 carries the sheet past the form cylinders 27, 28, each of which prints a different color on the sheet.

The sheet to be printed is therefore fed 120

automatically from the feed cylinder to the lower impression cylinder, past the lower form cylinders, then transferred automatically to the transfer cylinder, in turn automatically transferred to the upper impression cylinder, past the upper form cylinders, whence it is automatically delivered to suitable delivery mechanism, a portion of which is indicated at 75. A pair of form cylinders is shown coacting with each of the impression cylinders.

The various cylinders are caused to rotate at uniform peripheral speeds. The driving means for the cylinders is exemplified as an electric motor 81, the armature shaft 82 of which has a suitable pulley fixed thereto, about which and about a pulley 83 a suitable belt 84 is arranged to move for driving the pulley 83. The pulley 83 is fixed to a shaft 85 journaled in suitable bearings in a bearing stand 86, a gear 87 being fixed to said shaft and meshing with a gear 88 fixed to a shaft 89 rotating in a bearing 90 in the bearing stand. The gear 88 meshes with a gear 91, fixed to a shaft 92, which is the shaft of the transfer cylinder, journaled in a suitable bearing 93 adjustable in the frame.

The gear 91 is a double width gear, and meshes with gears 94, 95, fixed to the shafts of the impression cylinders 22, 23. Gears 96, 97, mesh with the gear 94, and gears 98, 99, mesh with the gear 95, the gears 96, 97, and 98, 99, being fixed to the respective shafts of the form cylinders. A gear 100 fixed to the shaft 61 of the feed cylinder meshes with the gear 94. (See Fig. 2.)

The impression cylinders 22, 23, are rotatable in on-impression positions with relation to the form cylinders, or in off-impression positions with relation thereto, and I have provided means for controlling said respective positions, and for moving said respective impression cylinders at predetermined points in their respective revolutions. I have provided means for timing said respective movements with relation to each other, in such manner that, when a sheet to be printed is improperly gripped or it is desired for other reasons not to print the same, the impression cylinder, which acts first on the sheets, shall be moved into off-impression relation only after a preceding sheet being printed by the same cylinder is fully printed by the form cylinders coacting therewith, and in such manner that said preceding sheet shall also be completely printed between the succeeding impression cylinder and its coacting form cylinders, after which only shall said succeeding impression cylinder be tripped into off-impression relation.

The infeeding edge of the sheet, when properly placed on the feed table with relation to the feed cylinder, is automatically

transferred from the gripping mechanism of each cylinder to the gripping mechanism of each succeeding cylinder, whether the impression cylinders are in on-impression relation or in off-impression relation.

The eccentric rock shaft 44 has an arm 101 fixed thereto. A rock shaft 102 is journaled in a bearing 103, in the side frame, and has arms 104, 105, fixed thereto. A link 106 is articulated with the arms 101 and 104. A link 107 is articulated with the arm 105 and an arm 108 on the eccentric sleeve 62. Similar parts are on the gear side of the machine, indicated by similar but primed reference numerals. The rock shaft 102 has an operating arm 109 fixed thereto, with which a link 110 is connected by an articulation 111. (See Figs. 1, 2, 3, 4 and 7.)

A rock shaft 115 is journaled in a bearing 116 in the side frame, and has an arm 117 fixed thereto. A link 118 has articulations with the arm 117 and an arm 119 on the eccentric shaft 54. Similar parts, indicated by similar but primed reference numerals are at the gear side of the machine. An operating arm 121 is fixed to the rock shaft 115. A link 122 is articulated at 123 with said arm.

Operating bars 125, 126, have endwise reciprocation imparted thereto, and have articulations 127, 128, respectively with the links 110, 122. The bars are exemplified as slidable longitudinally respectively in bearings 129, 130 and 131, 132, and on guideways 133, 134.

The bar 125 is provided with shoulders 135, 136, shown at the respective ends of a recess 137 in the bar. The bar 126 is provided with shoulders 138, 139, shown at the respective ends of a recess 140 in said bar. Arms 141, 142 are pivoted on pivot shafts 143, 144, respectively mounted in bearings 145, 146, of a housing 147. (See Figs. 5, 6, 8, 9 and 13.)

Oppositely extending pawls 151, 152, are pivoted to the arm 141, as on a pivot pin 153. These pawls are arranged to coact with the respective shoulders 135, 136, which shoulders are on hardened blocks 154, 155, let into recesses in the bar 125.

Oppositely extending pawls 161, 162, are pivoted to the arm 142, as on a pivot pin 163. These pawls coact with the respective shoulders 138, 139, which are on hardened blocks 164, 165, fixed in recesses in the bar 126. The arm 142 is provided with a lateral extension 166.

A cam assembly 171 comprises cam plates 172 and 173, secured to the respective sides of a fly-wheel 174, as by bolts 175, 176. The cam plate 172 is provided with a cam groove slot 177, and the cam plate 173 is provided with a cam groove 178. A roller 179 on a stud 180 on the arm 141 coacts with the

walls of the cam slot 177. A roller 181 on a stud 182 in the extension 166 of the arm 142, coacts with the walls of the cam slot 178.

The cam slot 177 has a low or dwelling portion 185, an ascending portion 186 and a descending portion 187. This cam is arranged to move the arm 141 for effecting movement of the lower impression cylinder 22 and the feed cylinder 29 in manner to be presently described. (See Figs. 5 and 6.)

The cam slot 178 is provided with a low or dwelling portion 188, an ascending portion 189 and a descending portion 190, for control of the arm 142, whereby to move the bar 126 in either direction by means of the pawls 161, 162, in manner to be presently described, in order to effect movement of the upper cylinder into on-impression or off-impression relation.

These movements are in synchronism with the rotations of said cylinders, so as to time the movements of the bars and consequent tripping of the cylinders in predetermined angular relations to the rotations of the cylinders for the purposes herein described.

The means for rotating the cam assembly 171 are shown as a gear 193 meshing with the gear 87, by means of which the gear train for the cylinders is controlled, the gear 193 being fixed to a shaft 194 journaled in bearings 195, 196, in the bearing stand 86 and in the side frame respectively. The shaft 194 has a bevel gear 197 fixed thereto, which meshes with a bevel gear 198, fixed to a shaft 199 in bearings 200, 201, of gear boxes 202, 203, fixed to the frame. A bevel gear 204, fixed to the shaft 199, meshes with a bevel gear 205 fixed to a shaft 206 journaled in a bearing 207 in the gear box 203 and in a bearing 208 in the housing 147. The shaft 206 has a pinion 209 fixed thereto, which meshes with a gear 210 on a fly wheel 211 fixed to a shaft 212, which also has the cam assembly 171 fixed thereto. The shaft 212 is journaled in bearings 213, 214. (See Figs. 2, 5 and 7.)

The manual control means for the tripping mechanism include treadle levers 221, 222, respectively carrying treadles 223, 224, the treadle levers being fixed to a rock shaft 225 in a bearing 226 in the frame of the machine. The rock shaft has an arm 227 fixed thereto. (See Figs. 1, 2 and 7.)

A rock shaft 228 is journaled in a bearing 229, in the base of the machine, and in a bearing 230, in the housing 147. An arm 231 is fixed to this rock shaft. A link 232 is articulated with this arm and with the arm 227.

The treadles and attendant parts just described are at the feed side of the machine. Similar parts indicated by similar but primed reference numerals are at the gear side of the machine.

An arm 235 is fixed to the rock shaft 228.

A link 236 is articulated with the arm 235 and with an arm 237 fixed to a rock shaft 238, which has arms 239, 240, fixed thereto in angular relation with each other. These latter arms carry rollers 241, 242, arranged to respectively coact with shelves 243, 244, on the pawls 151, 152, for raising said respective pawls into inactive relation or for permitting the pawls to coact respectively with the shoulders 135, 136. (See Figs. 1, 3, 6, 7, 8, 9, 13 and 14.)

The pawls 151, 152, are normally urged toward coactive relation with the shoulders 135, 136, by plungers 245, 246, in sockets 247, 248, in the operating arm 141, the plungers 245, 246, being spring-pressed by springs 249, 250, in said sockets toward said pawls. (See Figs. 13 and 14.)

The contact parts for the pawls, namely, the rollers 241, 242, are respectively normally held in actuated relation by being provided with notches 251, 252, into which a plunger 253 is arranged to be pressed by a spring 254 in a socket 255 of a locating plunger 256, reciprocating in a socket 257 in a socket-piece 258, bracketed from the side wall of the housing 147. A removable plate 259 is secured to the bottom of said socket-piece by screws 260. A spring 261 between the top of a socket 262 in the plunger 256 and said plate 259, urges the locating plunger into engagement with the bar 125.

The contact parts for the pawls are arranged to be in contacting positions at the limits of reciprocating movements of the operating arm to which they are pivoted, which correspond substantially to the corresponding respective limits of reciprocating movements of the operating bar coacting therewith. The locating plunger 256 is provided with a locating cam 265, which is arranged to be received in notches 266, 267, in the lower face of the reciprocating bar 125 at the limits of reciprocating movements of said bar, the lower face of said bar riding on the apex of said cam during times when the reciprocating bar is moving.

The coacting faces between said cam and said notches taper toward the middle of the cam, and they have sloping walls, so that the forceful endwise movement of the reciprocating bar 125 will not be interfered with, but that, upon such endwise movement of the bar, the cam will be caused to recede, for causing recession of the locating plunger, and consequent recession of the contact parts 241, 242, so as to place said contact parts out of range of the pawls 151, 152.

Referring to Figs. 1, 13 and 14, in which the parts are arranged for on-impression relation of the impression cylinders, the contact part 241 for the pawl 151 is in raised relation, for maintaining said pawl out of contact with its coacting shoulder 135 during the reciprocation of the arm 141, it being

understood that the operating arms 141, 142, reciprocate continuously during the operation of the printing press. When now, said arm 141 is moved to the right, its right hand pawl will remain out of contact with the right hand shoulder 135, leaving the bar 125 unactuated, for maintaining the cylinders in on-impression relation.

When the contact part 242 is placed in raised relation, the contact part 241 is lowered, and the locating cam 265, being received in the notch 266, the pawl 151 is permitted to drop into contact relation with the shoulder 135, for moving the operating bar 125 to the right. The locating plunger 256 is lowered by such movement of the operating bar for placing said contact parts 241, 242, out of action between the limits of movements of the operating bar, the locating cam 265 moving into the notch 267 when the operating arm 141 has completed its movement to the right, so as to move the contact part 242 into obstructing relation with the pawl 152, so that, upon the next return movement of said operating arm to the left, the pawl 152 will be out of range with the shoulder 136. If, however, the contact parts 241, 242, have been rocked in the meantime, or thereafter, for again lowering the contact part 242 and raising the contact part 241, the pawl 152 will, on said next return reciprocation of the operating arm, toward the left, engage the shoulder 136, for moving the operating bar 125 toward the left. There is a space 263 between said pawls and shoulders to readily permit such movement.

The parts just described are for controlling the pawls 151, 152, pivoted on the operating arm 141, and are instanced as located on the feed side of the housing 147, and as controlling the positions of the first or lower impression cylinder 22 and the feed cylinder 29. The pawls 161, 162, pivoted on the operating arm 142, for moving the second or upper impression cylinder 24, are pressed toward the operating bar 126, by plungers and springs similar to the plungers 245, 246, and springs 249, 250.

The off-impression movement and on-impression movement respectively of the second or upper impression cylinder is timed, in the present exemplification, so as to be three-fourths of a revolution of the cam assembly, or of said impression cylinders, later than the similar movements of the first impression cylinder and feed cylinder, in order that the same relations of impression cylinder and form cylinders to the sheet may prevail during coaction between the second impression cylinder and its form cylinders as prevailed during passage of said sheet between the first impression cylinder and its form cylinders.

The control for the second impression cylinder is automatically transferred from the

control means for the first impression cylinder. This is instanced as accomplished by the following means:

A rock-shaft 271 is journaled in suitable bearings in the housing 147, and has an arm 272 fixed thereto. A link 273 is articulated with the arm 272 and with an arm 274 fixed to a rock shaft 275, which has arms 276, 277, rigid therewith, these arms carrying contact parts 278, 279, shown as rollers, coacting with shelves, (similar to the shelves 243, 244), on the pawls 161, 162, pivoted to the operating arm 142, for controlling the direction of movement of the operating bar 126. (See Figs. 6, 8 and 9.)

The rock shaft 271 is operated by the operating bar 125, which coacts with plungers 281, 282, reciprocating in sockets 283, 284, in a housing 285, rigid with the bearing 129. These plungers respectively have racks 286, 287, thereon, which mesh with a gear 288 on a shaft 289 journaled in said housing, for causing movements of said plungers in opposite directions. The gear 288 meshes with a pinion 290 fixed to the rock-shaft 271. The plungers are reciprocated in opposite directions by the operating bar 125, which is shown accomplished by providing the operating bar with an operating lug 291, which is arranged to contact cam faces 292, 293, on the respective rack plungers 281, 282, the lug having its contact parts with said cams shaped for coaction with said cams, as by providing the same with coacting cam faces 294, 295. When the rack-plunger 282, is raised, it is received in a recess 296 in the operating bar 125. (See Fig. 12.)

The on-impression movement and the off-impression movement of the first or lower impression cylinder take place during the travel of the grippers thereon between the point or moment of paper taking by said grippers from the feed cylinder, which paper taking point or moment is in the radial line 301, (Fig. 16), which intersects the axis of rotation of the lower impression cylinder and the axis of rotation of the feed cylinder, and the point or moment of initiation of printing impression upon the sheet between the lower impression cylinder and the first form cylinder 25, which printing point or moment is in the radial line 302 which intersects the axis of rotation of the impression cylinder and the axis of rotation of the first form cylinder.

The on-impression movement of the lower impression cylinder takes place during the coaction of the ascending portion 186 of the cam 177 with the roller 179 on the arm 141, which takes place in the angle 303 between the radial lines 304, 305, imposed on said cam, which angle corresponds with the angle 306 between the radial lines 307, 308, imposed on the lower impression cylinder, as exemplified in Fig. 16. The lower cylinder

rotates in the direction of the arrow 309, and the cam 177 rotates in the direction of the arrow 310.

The off-impression movement of the lower impression cylinder takes place during succeeding angles of movements in said cam and impression cylinder respectively. The off-impression movement of the lower impression cylinder takes place during the coaction 10 of the descending portion 187 of said cam 177 with the roller 179, which takes place in the angle 311 between the radial lines 305 and 312, imposed on said cam, which angle corresponds with the angle 313 between the 15 radial lines 308 and 314, imposed on the lower impression cylinder.

The on-impression movement and the off-impression movement of the second or upper cylinder take place during the travel of the 20 grippers thereon in advance of the point or moment of initiation of printing impression upon the sheet between the upper impression cylinder and the third form cylinder 27 coacting therewith, which printing 25 point or moment is in the radial line 317 which intersects the axis of rotation of the impression cylinder and the axis of rotation of said third form cylinder.

The on-impression movement of the upper impression cylinder takes place during the coaction of the ascending portion 189 of the cam groove 178 with the roller 181 on the extension 166 of the arm 142, which takes place in the angle 318 between the radial 30 lines 319, 320, imposed on said cam, which angle corresponds with the angle 321 between the radial lines 322, 323, imposed on the upper impression cylinder, as exemplified in Fig. 15, through which the grippers of 40 the upper impression cylinder move during the on-impression movement of said cylinder.

The off-impression movement of the upper impression cylinder takes place during succeeding angles of movement in said cam 45 and impression cylinder respectively. The off-impression movement of the upper impression cylinder takes place during the coaction of the descending portion 190 of said cam 178 with the roller 181, which takes place in the angle 325 between the radial lines 320, 326, imposed on said cam, which angle corresponds with the angle 327 between the radial lines 323 and 328, imposed on the upper impression cylinder, through 55 which the grippers of the upper impression cylinder move during the off-impression movement of said cylinder.

The respective movements of the upper impression cylinder are three-fourths of a 60 revolution of said cylinder and of the cam portions therefor subsequent to the corresponding movements of the lower impression cylinder and the cam portions therefor, due to the angle of separation between the rollers 179 and 181, the angle of separation

between the high points of the cams 177, 178, and the relations of the latter to each other, as more fully illustrated in Figs. 6, 15 and 16. This belated movement of the second or upper cylinder with relation to the first 70 or lower cylinder is as heretofore explained, to permit a sheet being fed through the printing press to be fully printed by both said impression cylinders, if the impression cylinders have been set for on-impression relation, and to be wholly unprinted if the impression cylinders have been previously set 75 for off-impression relation.

In explaining the operation, it will be assumed that the impression cylinders are in 80 on-impression relation, as exemplified in Figs. 1 and 2, that the operating parts for the first or lower impression cylinder are at their limits of on-impression movements, as exemplified in Figs. 5, 6, 12, 14, 15, and 16; that the printing operations are taking place on successive sheets fed from the feed board 65; that the cam assembly 171 is rotating, there being a rotation of the cam assembly 90 for each rotation of the impression cylinders; that the operating arms 141, 142, are swinging, with the operating bar 125 for the lower or first impression cylinder moved to its rear limit of movement, namely to the left, and the operating bar 126 for the second or upper impression cylinder moved to its forward limit of movement, namely to the right; and that the pawls are moving idly, due to the pawl 151 being held in raised 100 relation in adjacency to its shoulder by the contact part 241, and the pawl 162 being held in raised relation in adjacency to its shoulder by the contact part 279.

Assuming further that a sheet is improperly gripped by the grippers on the feed cylinder 29, and that the operator desires that that sheet shall not be printed, the operator presses upon the treadle 224 at the feed side or upon the treadle 224' at the gear side of the press, for placing the control parts in relation for tripping the cylinders into off-impression relation. The actual tripping of the cylinders is, however, not initiated by the operating means until the grippers on the lower impression cylinder 110 gripping the infeeding edge of the sheet arrive approximately at their lowermost position in their circle of movement, instanced as at the radial line 308. This moment is 115 determined by the moment of arrival of the beginning of the descending portion 187 of the cam 177, exemplified by the radial line 305, at the position of the roller 179 on the arm 141. (See Fig. 6.)

The movement of the lower impression cylinder into off-impression relation takes place during the movement of the grippers in the angle 313 in advance of the normal printing contact position between said impression cylinder and the printing surface on the first 120 125

form cylinder, which corresponds in position with the angle 311 of the cam assembly.

Such off-impression movement of the lower impression cylinder also causes similar movement of the feed cylinder and places said cylinders in the relation to the form cylinders 25, 26, exemplified in Fig. 3.

The movement of these cylinders into off-impression relation is caused by the lowering of the contact part 241, which permits the pawl 151 to drop into engagement with the shoulder 135 on the operating bar 125, moving this operating bar forwardly during the forward swinging of the operating arm 141 just initiated (see Fig. 13).

Such forward movement of the operating bar 125 causes contact by the cam face 294 (see Fig. 12) with the cam 292 on the rack plunger 281, for pushing said rack plunger 20 downwardly, thereby rocking the shaft 271 and lowering the contact part 279 (see Figs. 8 and 9). This permits the pawl 162 to drop for engaging the shoulder 139 at the next rearward movement of the operating 25 arm 142, (see Fig. 4), for moving the operating bar 126 rearwardly, and thereby rocking the rock shaft 115 for moving the second or upper impression cylinder into off-impression relation, as exemplified in 30 Fig. 4.

Such tripping is, however, timed so as to delay the initiation of the tripping of the upper impression cylinder an interim, exemplified as three-fourths of a revolution 35 of the impression cylinders and of the cam assembly, after the initiation of tripping of the lower impression cylinder, so as to permit a preceding sheet being printed to pass between the upper impression cylinder and its plate cylinders while the former is still in on-impression relation, so as to completely print said preceding sheet previously printed by the lower impression cylinder and its coacting form cylinders.

The tripping of the lower impression cylinder takes place after the preceding sheet has been printed thereby, as exemplified in Fig. 3, and the tripping of the upper impression cylinder takes place only after said sheet is past printing position between the upper impression cylinder and its coacting plate cylinders.

Upon initiation of movement of the operating bar 125 forwardly, the locating cam 55 265 is pushed downwardly by the wall of the cam notch 266, for pushing the locating plunger 256 downwardly and placing the contact parts 241, 242, out of range of the pawls 151, 152, so as to permit any desired 60 control movement of said contact parts by the treadles, and to insure the completion of an initiated movement of the cylinders into on-impression position or off-impression position. In other words, the movements of 65 said cylinders for on-impression position or

for off-impression position are out of control of the operator when said respective movements are initiated, and the completions of the coactive rotative movements between said respective impression cylinders 70 and their coacting form cylinders are out of control of the operator being initiated, but the control of the operator for positioning the control parts for desired control movement at the next actuating movement of the 75 operating arms is practically continuous.

The locating plunger 256 and the contact parts 241, 242, are returned to normal positions upon completion of the forward movement of the operating bar 125, by the 80 reception of the cam 265 in the recess 267 in said bar. The reverse movement of the bar causes corresponding movements of the locating plunger and its contact parts.

If now it is desired to again place the impression cylinders into on-impression relation, the treadle 223 at the feed side or the treadle 223' at the gear side is depressed for placing the control means of the tripping mechanism into trip inducing positions. The 90 depression of these treadles causes the contact part 242 to be lowered and the contact part 241 to be raised for causing engagement of the pawl 152 with the shoulder 136 (see Figs. 6 and 13). The operating bar 125, being now at the forward limit of its movement, will at the next rearward movement of the operating arm 141 to the left, be moved into the positions shown in Figs. 1 and 13. This movement of the operating 100 bar causes rocking of the rock shaft 102 for moving the lower impression cylinder and the lower feed cylinder into on-impression relation, which movement takes place during movement of the grippers on the lower impression cylinder in the angle 306, and the coaction between the ascending portion 186 of the cam 177 with the roller 179 on the operating arm 141 in the angle 303 imposed on the cam 177.

The operating arms 141, 142, move in opposite directions with relation to each other for on-impression movement of the impression cylinders, and for off-impression movement of said cylinders.

The rearward movement of the operating bar 125 causes coaction between the cam face 295 thereon and the cam 293 on the rack plunger 282 for rocking the rock shaft 271 in reverse direction, and again lowering the contact part 278 and raising the contact part 279, for causing contacting between the pawl 161 and the shoulder 138 for moving the operating bar 126 forwardly and tripping the upper impression cylinder into on-impression relation, as shown in Figs. 1 and 2, which tripping occurs three-fourths revolution of said cylinders and said cam assembly after the tripping of the lower impression cylinder.

The tripping of the upper impression cylinder takes place during corresponding angles of rotation thereof and of the cam assembly as exemplified for instance in Fig. 15.

Having thus fully described my invention, what I claim as new, and desire to secure by Letters Patent, is:

1. In tripping mechanism for a printing press, the combination with a cylinder forming a member of a printing couple, of operating means for moving said cylinder for distance relation with another member of said printing couple and operable throughout a short angle of movement of said cylinder for shifting said cylinder, control means for said operating means, and means distancing said control means from said operating means during shifting movements of said cylinder.
2. In tripping mechanism for a printing press, the combination with a cylinder forming a member of a printing couple, of operating means for moving said cylinder for distance relation with another member of said printing couple and operable throughout a short angle of movement of said cylinder, said operating means constructed for placing said cylinder out of control of the operator for the major portion of the circle of movement of said cylinder, control means for said operating means, and means distancing said control means from said operating means during shifting movements of said cylinder.
3. In tripping mechanism for a printing press, the combination with a cylinder forming a member of a printing couple, of operating means constructed for causing approach and recession movements respectively of said cylinder for distance relation with another member of said printing couple and operable throughout closely related short angles of movements of said cylinder, control means for said operating means for controlling said respective movements, and means distancing said control means from said operating means during shifting movements of said cylinder.
4. In tripping mechanism for a printing press, the combination with a cylinder forming a member of a printing couple, of operating means for tripping said cylinder for distance relation with another member of said printing couple and operable throughout short angles of movements of said cylinder, control means for said operating means operable throughout substantially the whole of the circle of movement of said cylinder, and means distancing said control means from said operating means during shifting movements of said cylinder.
5. In tripping mechanism for a printing press, the combination with a cylinder forming a member of a printing couple, of operating means comprising movable actuating parts constructed for causing on-tripping movement of said cylinder and off-tripping movement of said cylinder in sequence, control means for said operating means comprising movable control parts coacting with said movable actuating parts, and means placing said control parts in inactive relation during on-tripping movement of said cylinder and into active relation at substantially the completion of said on-tripping movement, for initiation of off-tripping movement at the next sequential off-tripping movement of said operating means.
6. In tripping mechanism for a printing press, the combination with a cylinder forming a member of a printing couple, of operating means comprising intermittently operating parts causing on-tripping movement and off-tripping movement of said cylinder and operable throughout proximate short angles of rotations of said cylinder for said respective movements of said cylinder, control means comprising parts coacting with said operating means respectively for said on-tripping movement and for said off-tripping movement, and means whereby said last-named parts are operable during one of said movements for control relation for the other of said movements of said cylinder.
7. In tripping mechanism for a printing press, the combination with a cylinder forming a member of a printing couple, of operating means comprising intermittently operating parts causing on-tripping movement and off-tripping movement respectively of said cylinder and respectively operable throughout short angles of rotations of said cylinder for said respective movements, said short angles of rotations being closely related in time, control means comprising parts respectively coacting with said intermittently operating parts respectively for said on-tripping movement and said off-tripping movement, and means for shifting said last-named parts during one of said movements for control relation for the other of said movements of said cylinder.
8. In tripping mechanism for a printing press, the combination with an impression cylinder, grippers thereon, a form cylinder and a sheet positioning means, of operating means for moving one of said cylinders into on-impression relation and into off-impression relation sequentially in the order named in the angle of movement of said grippers between said sheet positioning means and said form cylinder in a single movement of said grippers in said angle, whereby to prevent printing by said cylinder after said cylinder has been moved into printing relation in said single angle of movement of said grippers, and control means for said operating means.
9. In tripping mechanism for a printing press, the combination with an impression

cylinder, grippers thereon, a form cylinder and a sheet positioning means, of operating means for moving said impression cylinder into on-impression relation and into off-impression relation in the angle of movement of said grippers between said sheet positioning means and said form cylinder, control means for said operating means, and actuating means for said control means operable substantially throughout the balance of the circle of movement of said impression cylinder, and constructed and arranged for placing said control means into positions for coaction with said operating means in the angle of movement of said grippers for on-impression relation, whereby said operating means move said impression cylinder into off-impression relation in the angle of the movement of said grippers between said on-impression angle and said form cylinder.

10. In tripping mechanism for a printing press, the combination with an impression cylinder, grippers thereon, a form cylinder and sheet positioning means, of operating means for moving said impression cylinder into on-impression relation and into off-impression relation throughout successive angles of movement in a single movement of said grippers between said sheet positioning means and the point of printing initiation between said cylinders, the sum of which angles is substantially less than one-half the complete circle of movement of said grippers, control means for said operating means, and means for moving said control means operable throughout substantially the whole of the circle of movement of said grippers.

11. In tripping mechanism for a printing press, the combination with an impression cylinder, grippers thereon, a form cylinder and sheet positioning means, of operating means for moving said impression cylinder into on-impression relation and into off-impression relation throughout successive angles of movement of said grippers between said sheet positioning means and said form cylinder, control means for said operating means, means for moving said control means operable throughout substantially the whole of the circle of movement of said grippers, and means automatically placing said control means in inactive relation during said movements of said impression cylinder.

12. In tripping mechanism for a printing press, the combination with an impression cylinder, grippers thereon, a form cylinder and sheet positioning means, of reciprocating operating means moving in opposite directions throughout successive angles of movement of said grippers between said sheet positioning means and said form cylinder for moving said impression cylinder respectively into on-impression relation and into off-impression relation, control

means for said operating means and means for rendering said control means inactive during said movements of said impression cylinder.

13. In tripping mechanism for a printing press, the combination with a plurality of printing couples each comprising a cylinder arranged to be tripped, of operating means for each of said cylinders for tripping the same, control means for each of said operating means, manual setting means for one of said control means, means between the operating means controlled by said one of said control means and the other of said control means for automatically setting said other of said control means according to the setting of said manually set control means, said operating means comprising means for tripping said cylinders in sequence, and means automatically rendering the control means set by said manual setting means inactive.

14. In tripping mechanism for a printing press, the combination with a plurality of printing couples each comprising a cylinder arranged to be tripped, of means whereby said printing couples are caused to print in sequence, operating means for each of said cylinders for tripping the same in the sequence of their printing relations, control means for each of said operating means, setting means for each of said control means, manual mechanism connecting with one of said setting means, and means rendering the control means arranged to be set by said one of said setting means inactive during tripping movement of the cylinder controlled thereby.

15. In tripping mechanism for a printing press, the combination with a cylinder to be tripped, of shifting means for said cylinder, a rotary cam, means for rotating said cylinder and said cam in synchronism, a pivoted arm having operative connection with said cam for being operated by said cam, a reciprocating bar having operative connection with said shifting means, movable connecting means between said arm and said bar, control means controlling the positions of said connecting means, and means for causing inactive relation of said control means.

16. In tripping mechanism for a printing press, the combination with a cylinder to be tripped and shifting means for said cylinder, of a rotary cam, a pivoted arm having operative connection with said cam for being operated by said cam, a reciprocating bar having operative connection with said shifting means, oppositely extending pawls between said arm and said bar for transmitting the movements in opposite directions of said arm to said bar, means for holding said respective pawls in inactive relations, actuating means for the latter, and means for causing inactive relation of said holding means.

17. In tripping mechanism for a printing press, the combination with a cylinder to be tripped and shifting means for said cylinder, of a rotary cam, a pivoted arm having operative connection with said cam for being operated by said cam, a reciprocating bar having operative connection with said shifting means, a pair of oppositely extending pawls pivoted to said arm, said bar 10 provided with shoulders respectively coacting with said pawls for transferring movements in opposite directions of said arm to said bar, contact parts for said respective pawls, means moving said contact parts into coactive relations with said respective pawls for moving said respective pawls into inactive relations with said shoulders, and means automatically moving said contact parts out of coactive relations with said pawls. 15
18. In tripping mechanism for a printing press, the combination with a cylinder to be tripped and shifting means for said cylinder, of a reciprocating operating member, a reciprocating bar having connection with 20 said shifting means and movable in opposite directions respectively for on-tripping movement and for off-tripping movement of said cylinder, oppositely extending pawls and coacting parts therefor operative between said reciprocating operating member and said bar, there being an idle operating space between said pawls and said coacting parts, control parts for said respective pawls constructed for operating to permit movement 25 of said respective pawls into active relation or inactive relation with said coacting parts, and means placing said control parts in inactive relation during reciprocating movement of said bar. 30
19. In tripping mechanism for a printing press, the combination with a cylinder to be tripped and shifting means for said cylinder, of a reciprocating bar having operative connection with said shifting means, a reciprocating operating member, oppositely extending pawls and shoulders therefor operatively located between said operating member and said bar, a rocker part, contact parts thereon for said respective pawls for 35 controlling the positions of said pawls with relation to said shoulders, means for actuating said rocker part, and means for moving said rocker part into inactive relation with said pawls. 40
20. In tripping mechanism for a printing press, the combination with a cylinder to be tripped and shifting means for said cylinder, of a reciprocating bar having operative connection with said shifting means, a reciprocating operating member, oppositely extending pawls and shoulders therefor operatively located between said operating member and said bar, a rocker part, contact parts thereon for said respective pawls for 45 controlling the positions of said pawls with relation to said shoulders, means for actuating said rocker part, and means for moving said rocker part into inactive relation with said pawls. 50
21. In tripping mechanism for a printing press, the combination with a cylinder to be tripped and shifting means for said cylinder, of a reciprocating operating member, a reciprocating bar, operating means between said operating member and said bar for causing reciprocations in similar directions between the same, control means for the latter, and a mounting for said control means, and said bar and said mounting provided with cam means whereby to retract said control means between the limits of reciprocating movements of said bar. 55
22. In tripping mechanism for a printing press, the combination with a cylinder to be tripped and shifting means for said cylinder, of a reciprocating operating member, a reciprocating bar having operative connection with said shifting means, oppositely extending spring pressed pawls and shoulders therefor operatively located between said operating member and said bar, control parts for said respective pawls, a spring-pressed mounting normally moving said control parts toward said pawls, and means for actuating said control parts, and said bar and said mounting provided with cam means whereby to resiliently move said mounting away from said bar for placing said control parts into inactive relations with said pawls. 60
23. In tripping mechanism for a printing press, the combination with a plurality of printing couples each comprising a cylinder to be tripped, of shifting means for said respective cylinders for tripping the same, similar rotary cams having coincident axes arranged in different angular relations, a pivoted arm for each of said cams, a reciprocating bar for each of said shifting means, movable connecting means between each of said arms and its bar, control means for each of said connecting means controlling the positions of said connecting means, each of said reciprocating bars and its arm forming a pair of reciprocating elements, and means for operating said control means for one of said connecting means including one of said reciprocating elements. 65
24. In tripping mechanism for a printing press, the combination with a plurality of printing couples each comprising a cylinder to be tripped, of shifting means for said respective cylinders for tripping the same, similar rotary cams having coincident axes arranged in different angular relations, a pivoted arm for each of said cams, a reciprocating bar for each of said shifting means, 70

movable connecting means between each of said arms and its bar, control means for each of said connecting means controlling the position of said connecting means, and connecting means between said control means including one of said bars.

25. In tripping mechanism for a printing press, the combination with a plurality of printing couples each comprising a cylinder to be tripped, of shifting means for said respective cylinders for tripping the same, similar rotary cams having coincident axes arranged in different angular relations, a pivoted arm for each of said cams, a reciprocating bar for each of said shifting means, said arms movable in opposite directions for similar shifting movements of said cylinders, movable connecting means between each of said arms and its bar, control means for each of said connecting means controlling the positions of said connecting means, and means rendering said control means inactive.

26. In tripping mechanism for a printing press, the combination with a plurality of printing couples each comprising a cylinder to be tripped, of shifting means for said respective cylinders for tripping the same, an actuated part for each of said shifting means, a rotary cam for each of said actuated parts, said cams having coincident axes, control means for each of said actuated parts, and means for placing one of said control means in inactive relation with its actuated part whereby to complete shifting movement of said cylinders upon initiation of said shifting movement of one of said cylinders.

27. In tripping mechanism for a printing press, the combination with a plurality of printing couples each comprising a cylinder to be tripped, of shifting means for said respective cylinders for tripping the same, a reciprocating bar for each of said shifting means, a pivoted arm for each of said bars, movable connecting means between each of said arms and its bar, control means for each of said connecting means, a rotary cam for each of said arms, said cams having coincident axes, means automatically transmitting control relation between one of said control means and another of said control means, and means for placing said one of said control means in inactive relation with its connecting means whereby to complete shifting movement of said cylinders upon ini-

tiation of shifting movement of one of said cylinders.

28. In tripping mechanism for a printing press, the combination with a plurality of printing couples each comprising a cylinder to be tripped, of shifting means for each cylinder for tripping the same, operating means for each of said shifting means comprising movable connecting parts, each of said operating means comprising a reciprocating element, control means for each of said connecting parts controlling the positions of said connecting parts, and automatic actuating means for one of said control means comprising the reciprocating element of the other of said operating means, a pair of oppositely reciprocating racks, gearing operatively connected therewith, and operating means between said gearing and said last-named control means, said reciprocating element and reciprocating racks provided with coacting motion transmitting parts.

29. In tripping mechanism for a printing press, the combination with a plurality of printing couples each comprising a cylinder to be tripped, of shifting means for each of said cylinders for tripping the same, operating means for each of said shifting means, and control means for each of said operating means, the control means for one of said operating means including oppositely moving racks, cam means between said racks and the other of said operating means, a rockable member for controlling said last-named control means, and gearing between said rockable member and said racks.

30. In tripping mechanism for a printing press, the combination with a plurality of printing couples each comprising a cylinder to be tripped, of shifting means for said respective cylinders for tripping the same, a reciprocating bar for each of said shifting means, means for operating said bars, control means for each of said operating means, means for actuating one of said control means comprising reversely reciprocating racks provided with cam faces, the reciprocating bar of the other of said operating means provided with coacting cam faces, a rocker part having operative connection with said one of said control means, and gearing between said racks and said rocker part for operating said rocker part.

In testimony whereof, I have hereunto signed my name.

STEWART L. SHARPLESS.
